UNITED STATES PATENT OFFICE.

CARL WINKLER, OF BERNE, SWITZERLAND.

PROCESS FOR PRODUCING MOLDS FOR CASTING STEREOTYPE-PLATES.

1,104,595.

Specification of Letters Patent. Patented July 21, 1914.

No Drawing.

Application filed December 26, 1913. Serial No. 803,761.

To all whom it may concern:

Be it known that I, CARL WINKLER, a citizen of the Swiss Republic, residing at Berne, in the Swiss Republic, have invented a new and useful Improved Process for Producing Molds for Casting Stereotype-Plates, of which the following is a specification.

It is usual, in making molds for casting stereotype plates, to carry out all operations, such as turning, planing or shaping, while the mold is in a cold condition. The mold must however be raised to a certain temperature before being used for casting, as otherwise the plates produced cannot be employed for printing. Plates cast in such molds when it is in a hot condition must be subsequently turned or shaped, in order to receive the exact dimensions required. This subsequent treatment of the plates is necessary, principally because the mold, in a hot condition, owing to the expansion and contraction of the metal, acquires dimensions which differ from those the plates should have. Now experiments have shown that stereotype plates of the desired dimensions can be better obtained by forming (for example, boring, planing, etc.) the mold in a hot condition. It is of course desirable to heat the mold while being formed to a temperature which corresponds to that to which it must be raised for casting.

In carrying out the invention steam, hot gases, hot air, or a hot liquid may be introduced into hollow chambers provided in the mold during the turning operation. If the mold has no special hollow chambers a heating device may be employed, which can have any suitable construction, and may consist, for example, of pipes containing some hot agent and brought into contact with the mold.

The difference in printing plates cast in molds made in a hot condition, compared with plates cast in molds made in a cold condition, as heretofore usual, are so considerable that a subsequent planing or boring of said plates is not necessary.

What I claim and desire to secure by Letters Patent of the United States is:—

The process for producing molds for casting stereotype plates, which consists in finishing said molds at about a temperature to which said molds are raised when the plates are cast in said molds.

In testimony whereof I have signed my name to this specification in the presence of two subscribing witnesses.

CARL WINKLER.
